UNITED STATES PATENT OFFICE.

JOHN B. GURY, OF ST. LOUIS, MISSOURI.

CLOTH-CUTTING MACHINE.

Application filed April 7, 1924. Serial No. 704,566.

This invention relates to cloth cutting machines and the like, and has for its objects to provide a simple and efficient safety device or guard for the cutting blade of such machines, which will not interfere with the regular function and operation of the cutting blade, yet will prevent serious accidental injury to the operator in handling and manipulating the machine.

In machines of this character, there is usually provided either a rotating circular blade or a reciprocating blade for cutting the cloth or material as the machine is moved by the operator against the latter on a work-table. Obviously, the cutting portion of the blade is necessarily exposed considerably, and the blade operating at a relatively high speed sometimes seriously cuts the operator's hands and is liable to completely sever a finger when brought into contact therewith.

Guards of various kinds have been provided on machines which protect only as to a portion of the cutting blade, while others are made adjustable so as to take care of piles of cloth or material of different thicknesses. The latter type of guard is usually more or less intricate in construction and in many cases only serves to guard that portion of the cutting blade above the pile of cloth or material.

The present invention, therefore, aims to provide a guard throughout the entire exposed portion of the cutting blade, and it consists essentially in the provision of a stationary, relatively thin member or plate approximating the thickness of the cutting blade and placed alongside of the latter, the edge portion of said guard member or plate being blunt and set back a short distance from the exposed cutting edge of the blade. The invention further consists in providing for the adjustment of the guard to compensate for the reduction in diameter or width of the cutting blade due to wearing away thereof in the course of resharpening it from time to time. The invention still further consists in the parts and in the combination and arrangements of parts hereinafter described and set forth in the appended claims.

In the accompanying drawings illustrating a practical embodiment of the invention,

Figure 1 is a side elevation of an ordinary cloth cutting machine having a rotary cut-

ting blade, and showing the relation of the safety guard therewith;

Figure 2 is a view of the guard member detached;

Figure 3 is a fragmentary view, on an enlarged scale, looking at the opposite side of the machine from that shown in Figure 1, parts being broken away or removed; and

Figure 4 is a fragmentary section, taken substantially on the line 4-4 of Figure 1, to illustrate the correlation of the guard member to the forward working edge of the cutting blade and supporting standard of the machine.

Referring now to the drawings, the number 1 designates the base-plate of the machine, having the usual tapered edge portions so as to ride under the cloth or material on the work-table. Extending upward from the base-plate is the standard 2, at the top of which is an electric motor 3, and at the rear of which is the manipulating handle 4.

On the shaft of the motor 3 is a worm-screw 5 which engages and drives a gear 6, which latter in turn engages and drives a second gear 7, the standard 2 being internally recessed to accommodate said gears and the circular cutting blade 8, which latter is fixed axially to the gear 7 so as to rotate therewith. The blade 8 projects through a slot in the forward portion of the standard, and the standard is obviously tapered on each side in the region of the exposed portion of the blade so as to be wedge-like in order to minimize resistance to the cloth or material and not interfere with the cutting operation.

The guard member, comprising the plate 9, is placed alongside of the cutting blade 8, its exposed edge portion 10 being shaped to conform substantially to the curvature of the periphery of the blade, and its edge, which is relatively blunt as compared with sharpened edge of the blade, being set normally rearward of the latter. The outer corner of the guard is preferably rounded off a bit, as at 11 (see Figure 4) so as to take away the sharpness of the edge and yet leave it sufficiently blunt for the purposes intended.

The guard plate 9, for the purpose of clearing the gear 7 and hub portion of the cutting blade 8, has a central opening 12 which is somewhat elongated or elliptical

to permit forward and backward adjustment of the plate. On the plate is a lug or rib 13 which is fitted slidably in an elongated counterpart recess 14 in the standard 2, the lug or rib having a screw-threaded aperture 15 (see Figure 2) for the reception of a fastening screw 16 which is inserted from the outside of the standard through a slot 17 therein. In this way the forward edge of the guard member may be readily adjusted with respect to the cutting edge of the cutting blade so as to take care of any reduction in the diameter of the blade due to the grinding away thereof in the course of resharpening.

By the provision of a guard of this character and the same being stationary while the cutter is rotating, it offers considerable resistance to solid flesh or bone so as to prevent the cutting blade from going deeper than the extent of its slight projection from the edge of the guard, thereby enabling the operator to get his hand or finger away from the cutting blade before a relatively deep incision is made and at least avoid complete severance of a bone or the hand or finger. At the same time, the guard will not interfere with the cutting of cloth or material of a pliable character through which the ordinary cutting blade will make its way in the customary manner.

The invention admits of considerable modification within the spirit thereof as defined by the appended claims. Therefore, it is not limited to the specific construction and arrangement shown in the accompanying drawings.

What is claimed is:

1. In a machine for cutting cloth and the like, a composite cutting element comprising a travelling cutting blade proper and a correlated stationary blade-like member in juxtaposition to said travelling blade, said

stationary member having a relatively blunt edge terminating inward from the cutting edge of said travelling blade a relatively short distance and extending substantially parallel with and throughout the exposed extent of said cutting edge.

2. In a machine for cutting cloth and the like, in combination with a travelling cutting blade, of a guard comprising a normally stationary member in juxtaposition to said blade, said member approximating the same thickness of the blade and having a relatively blunt edge terminating inward from the cutting edge of said blade a relatively short distance and extending substantially parallel with and throughout the exposed extent of said cutting edge.

3. In a machine for cutting cloth and the like, in combination with a travelling cutting blade, of a guard member having a portion approximating the same thickness of the blade and located in juxtaposition to the exposed working portion of the latter, said guard member having a relatively blunt edge extending substantially parallel with and throughout the exposed cutting edge of said blade, and means for effecting adjustment of said guard member relative to the cutting edge of said blade and for holding said guard member normally stationary in its adjusted position.

4. In a machine for cutting cloth and the like, comprising a base-plate, a standard on said base-plate, a rotating, circular cutting blade on said standard, and a stationary guard member on said standard in juxtaposition to said cutting blade, said guard member having a relatively blunt, arcuate edge portion terminating inward from the cutting edge of said blade and extending substantially parallel with and throughout the exposed extent of said cutting edge.

J. B. GURY.
